2,660,716

METHOD AND APPARATUS FOR ASCERTAIN-
ING TIME OF EXPLOSIONDavid M. McFarland, West Chester, Pa., assignor
to Atlas Powder Company, Wilmington, Del.,
a corporation of Delaware

Application May 6, 1950, Serial No. 160,518

7 Claims. (Cl. 340—15)

1

An object of the present invention is the provision of an improved method for ascertaining the time at which an explosion occurs.

Another object of the present invention is the provision of an improved method for ascertaining the time of explosion of an electric explosion initiator.

Still another object of the present invention is the provision of an improved method for ascertaining the time of explosion of an explosive charge initiated by an electric explosion initiator.

A further object of the invention is the provision of an improved method for ascertaining the instant of firing of an explosive contained in the bore hole and initiated by an electric blasting cap.

Still further objects of the invention are the provision of apparatuses to accomplish the foregoing objects.

Other objects of the invention will be apparent from the following description.

In some explosive operations, and particularly in geophysical prospecting with the seismograph, it is desirable to ascertain the time of firing of an explosive charge precisely. Often the possible error should be limited to a fraction of a millisecond.

Several methods have been proposed for making such firing time determinations. Most of these depend upon ascertaining the time of firing of the electric blasting cap used to initiate the explosive charge. One such method involves the winding of a current carrying wire around the cap used, or around another cap fired in series with the cap used, and then determining the time of breaking of the electric current passing through the wire. Unfortunately it has been found that such a wire does not always break as instantaneously as may be desired. Furthermore, it is awkward to provide a current-carrying wire around the cap used, and, when a current-carrying wire is wrapped around a cap in series with the cap used, error is likely to be introduced due to the fact that electric blasting caps in series often do not detonate with sufficient simultaneity.

Probably the most common method of determining the time of firing of a seismograph charge initiated by an electric blasting cap involves a determination of the time the bridge wire in the firing circuit of the cap breaks due to the explosion of the cap. However, from numerous tests with the cathode ray oscilloscope it has become evident that the results obtained by this method are subject to appreciable variation. For one

2

thing any inductance in the firing circuit is apt to provoke an arc of unknown duration when the circuit is disrupted. Moreover, since explosions produce ionized gases, conditions in the bore hole are conducive to the preservation of current flow in the firing circuit after the bridge wire of the blasting cap has been broken.

It has been found, in accordance with the present invention, that, if an electric potential is impressed between the firing circuit of an electric explosion initiator and a point normally insulated from the firing circuit but in the locus of explosion, when explosion occurs a current will pass by virtue of the impressed potential. Thus ascertaining the time of passage of a current ascertains the time of explosion. It is postulated that the current is carried by ionized gases formed in the explosion.

In the performance of the invention, the point normally insulated from the firing circuit may be any point positioned in the locus of explosion so that it comes into conductive relation with the firing circuit. Thus, with a common electric blasting cap having a metal shell insulated from its firing circuit, a potential may be impressed between the shell and the firing circuit; or where, as is usually the case, the explosion, the time of which is to be ascertained, takes place in the ground, the potential may be impressed between the firing circuit and ground.

The particular device used for determining the time of passage of a current between the firing circuit and a point in the locus of the explosion is no part of the present invention. Any device which will ascertain the time of commencement of an electric current may be used. An oscilloscope, such as the cathode ray oscilloscope or the Duddell oscilloscope, is usually satisfactory. The cathode ray oscilloscope appears to be the instrument most advantageously used and will be the instrument referred to as illustrative in the following description.

The potential impressed between the firing circuit and a point in the locus of explosion may be the same potential used to pass a current through the firing circuit to fire the cap. When this is done, however, it is desirable to include a resistance in the side of the cap firing circuit which is common in potential to the point external to the firing circuit in the locus of the explosion. If no such resistance is present the potential impressed external to the firing circuit may be short circuited by a continuance of a flow of current through the firing circuit after explosion has taken place. Such a continuance of flow of cur-

rent might arise, for example, due to reestablishment of contact between leg wires in the course of the explosive action or due to passage of current through the ionized gases resulting in the course of the explosion. While the resistance used should be sufficient to divert current to the ground circuit it should not be so large that it prevents the passage of an adequate firing current.

The invention will be further and more specifically described by reference to the drawings in which:

Figure 1 is a side elevation, partly in section, of an electric blasting cap especially adapted for use in the present invention and (on a comparatively reduced scale) an electrical circuit which will bring about the accomplishment of the method of the invention;

Figure 2 represents a side sectional view of a bore hole containing an explosive charge and a blasting cap which is connected to a circuit such that the method of the present invention can be accomplished;

Figure 3 is a view similar to Figure 2 showing a modified bore hole and a modified circuit; and

Figure 4 is a diagrammatic representation of a multiple switch blasting machine suitable for use in the circuit of Figure 3.

As shown in Figure 1 11 represents a metal shell into the bottom of which are pressed base charge 13, primary detonator charge 15, and flash charge 17. The particular composition and number of these explosive charges is no part of the present invention, but for purpose of illustration it may be stated that base charge 13 may be tetryl, the primary detonator charge 15 may be nitromannite, and the flash charge 17 may be a mixture of nitromannite and diazo di-nitrophenol. 19 represents generally a conventional electric match made up of insulating sheet 21 on each side of which are affixed metal terminal sheets 23 and 25. 21 represents a match head made up of an ignition composition, for example, a nitrocellulose lacquer containing copper acetylid, surrounding the lower portion of terminal sheets 23 and 25 and a bridge wire connecting them (not shown). 29 represents a sealing plug which may, for example, be made of rubber. Connected to match head 19 and extending through plug 29 are leg wires 31 and 33 covered by insulation 35 and 37 respectively. Also extending through plug 29 is wire 39 covered with insulation 43. It will be noted that wire 39 is bent around the bottom of plug 29 so as to insure its being in contact with shell 11.

The electric blasting cap just described is unusual in the inclusion of third wire 43. It is more fully described in copending application, Serial No. 115,439, filed September 13, 1949, for Electric Explosion Initiator, of which this application is a continuation in part.

Leg wire 31 is connected to one pole of a conventional blasting machine 43 and leg wire 33 is connected to the other pole of blasting machine 43. Wire 45 is connected to the same pole of the blasting machine as is leg wire 33 and connects the blasting machine to an oscillograph. The oscillograph is in turn connected to a battery 47 which in its turn is connected to the third wire 39 of the electric blasting cap. Thus, by means of battery 47 a potential is impressed between shell 11 and the firing circuit of the blasting cap through the oscillograph. When blasting machine 43 is operated and a current passes through leg wires 31 and 33 to match 19, the blasting cap fires. The

ionized gases so formed permit the passage of a current between the firing circuit and third wire 39. The making of this circuit is recorded on the oscillograph and indicates the time of firing of the blasting cap.

It is not necessary that third wire 39 be in electrical contact with shell 11. It may simply terminate inside the initiator so as to provide a pole for passage of current through the ionized atmosphere resulting after the cap has fired. However, when wire 39 is connected with shell 11 as is preferred, a larger contact is, of course, provided.

The invention may also be performed with ordinary electric blasting caps, and an arrangement for doing this is shown in Figure 2 wherein 49 represents a bore hole, 51 represents an explosive charge, 53 represents an electric blasting cap, 55 and 57 represent the two leg wires of electric blasting cap 53, and 59 represents stemming material loaded above charge 51. Many bore holes used in seismograph blasting have metal casings extending part or all of their length. Such a casing is shown at 61. Blasting cap 53 is connected by its leg wires 55 and 57 to a source of current for firing it, and another source of current is connected to casing 61 of bore hole 49 by means of wire 63. The second source of current is connected by wire 65 through an oscillograph and wire 67 to the firing circuit of the blasting cap so that the second source of current and the oscillograph are serially connected between casing 61 and the firing circuit.

In operation of the circuit just described the second source of current impresses a potential through the oscillograph between ground and the firing circuit of the blasting cap. The first source of current fires the blasting cap. When the oscillograph registers the starting time of passage of a current the time of explosion has been ascertained.

While both sources of current may be applied simultaneously, it is usually desirable to impress the potential through the oscillograph a short time before closing the firing circuit of the blasting cap. However, to avoid danger from accidental firing of the electric blasting cap in the event it should have had its firing circuit grounded to its shell during manufacture, it is not usually desirable to impress the potential between the firing circuit and ground until all steps prior to firing have been completed.

As has been stated above, the same source of current may be used both to fire the cap and to register the time of firing the cap. Figure 4 illustrates a manner in which a multiple switch blasting machine may be used both as a single source of current and as a means for impressing the potential between ground and the firing circuit just prior to the time of firing of the blasting cap. A number of elements in Figure 3 are similar to elements appearing in Figure 2 and are represented by primed numbers corresponding to numbers used in Figure 2. In the ground is bore hole 49' containing an explosive charge 51' in which is placed an electric blasting cap 53' provided with leg wires 55' and 57' leading out of bore hole 49'. Stemming 59' is packed above charge 51' in bore hole 49'. Leg wire 55' leads to resistance 75 which is connected in series with multiple switch blasting machine 77 through wire 79.

Multiple switch blasting machine 77 is diagrammatically shown in more detail in Figure 4 and is fully described in U. S. Patent 2,081,633, issued May 25, 1937 for "Method of and

Apparatus for Firing Explosive." It is operated by depressing handle 106. Rack bar 105 when thrust downwardly by means of handle 106 imparts a quick spin through suitable gears (not shown) to the armature of a generator represented diagrammatically at 81. After the generator has picked up speed and built up electric energy, the lower end of the rack bar acts upon a cam lug 109 to close an electric circuit by bringing the contact foot 110 into engagement with contact strip 111. Contact strip 111 is connected by a conductor 117 with binding post 118, and contact foot 110 is connected by conductor 119 to the generator windings indicated at 121, these latter being connected by a conductor 122 with binding post 123.

After contact foot 110 has been brought into engagement with contact strip 111, rack bar 105 continues its downward movement and through cam lug 112 thrusts contact foot 113 against a contact strip 114 thereby closing a second circuit. Contact strip 114 is connected by a conductor 115 with binding post 116, and contact foot 113 is connected by conductor 120 through the generator windings 121 and conductor 122 with binding post 123.

Referring again to Figure 3 it is seen that wire 79 is connected to binding post 116 of multiple switch blasting machine 77. Leg wire 57' is connected to common terminal 123 of blasting machine 77. Terminal 118 is connected to ground through an oscilloscope by means of wires 83 and 84. Thus, as blasting machine 77 is operated a potential is first impressed between the firing circuit of the blasting cap 53' through the ground and the oscilloscope; then, while that potential is still applied, a current is passed through the blasting cap firing circuit (and through resistance 75) firing the cap. As the explosion takes place, the potential impressed between the cap firing circuit and ground causes the passage of a current through the oscilloscope thus recording the time of explosion. Resistance 75 insures that current will not fail to pass through the oscilloscope in the event that a closed circuit occurs between leg wires 55' and 57' after the explosion.

What is claimed is:

1. A method for ascertaining the time of fir-

ing of an explosion initiated by an electric explosion initiator which comprises impressing an electrical potential between the firing circuit of said initiator and a point normally insulated from said firing circuit but in the locus of explosion, firing said initiator, and ascertaining the time at which a current passes by virtue of said potential.

2. Apparatus for ascertaining time of an explosion, comprising an electric explosion initiator, a firing circuit extending to said initiator, an auxiliary circuit including a portion of said firing circuit and also including a conductive path extending to a point normally insulated from the firing circuit but in the locus of the explosion, whereby said auxiliary circuit is normally open-circuited but current is caused to flow therein by the explosion, and current-responsive recording means included in said auxiliary circuit to respond to current flow therein and to indicate the time of the explosion.

3. Apparatus according to claim 2, wherein said conductive path comprises a connection extending to a point within the explosion initiator but normally insulated from the firing circuit.

4. Apparatus according to claim 3, wherein the explosion initiator is provided with a metal shell normally insulated from the firing circuit, and said conductive path comprises a connection extending to said metal shell.

5. Apparatus according to claim 2, wherein said conductive path extends through the ground.

6. Apparatus according to claim 2, including a single source of voltage, and means for connecting said source both in said firing circuit and in said auxiliary circuit.

7. Apparatus according to claim 6, including means for connecting said source first in said auxiliary circuit and then in said firing circuit.

DAVID M. MFARLAND.
